DESIGN FOR A COMBINATION RADIO LAMP, LOG, AND DAILY REMINDER OR THE LIKE

Marvin A. Clark, Los Angeles, Calif.

Application January 19, 1939, Serial No. 82,450

Term of patent 7 years

To all whom it may concern:

Be it known that I, Marvin A. Clark, a citizen of the United States, residing at Los Angeles, in the county of Los Angeles and State of California, have invented a new, original, and ornamental Design for a Combination Radio Lamp, Log, and Daily Reminder or the like, of which the following is a specification, reference being had to the accompanying drawing, forming part thereof.

Fig. 1 is a perspective view of a combination

radio lamp, log, and daily reminder, showing my new design.

Fig. 2 is an end view of the same.

The sides opposite the sides disclosed in Figure 1 are plain.

I claim:

The ornamental design for a combination radio lamp, log, and daily reminder or the like, as shown and described.

MARVIN A. CLARK.
